UNITED STATES PATENT OFFICE.

EDGAR F. HATHAWAY, OF DORCHESTER, MASSACHUSETTS.

CAN OR RECEPTACLE FOR THE RECEPTION OF CHENILLE STRANDS OR THE LIKE
AND PROCESS OF USING THE SAME.

Application filed March 5, 1921. Serial No. 449,886.

To all whom it may concern:

Be it known that I, EDGAR F. HATHAWAY, a citizen of the United States, and a resident of Dorchester, in the county of Suffolk 5 and State of Massachusetts, have invented an Improvement in Cans or Receptacles for the Reception of Chenille Strands or the like and Processes of Using the Same, of which the following description, in connection with 10 the accompanying drawings, is a specification, like characters on the drawings representing like parts.

This invention relates to cans or receptacles particularly intended for the reception 15 of chenille strands or strips, and to the process of using the same. Obviously, however, the receptacle may be used for roving or for similar strand-like material.

In order that the principle of the invention 20 may be readily understood, I have disclosed a single embodiment of the invention in the accompanying drawing, wherein—

Fig. 1 is a plan view of one of the covers;

Fig. 2 is an underneath plan view of said cover;

Fig. 3 is a vertical section upon the line 3—3 of Fig. 1 and taken through the can and through both the covers;

Fig. 4 is a detail in vertical section upon an enlarged scale showing the locking means for one of the covers; and

Fig. 5 is a detail in vertical section upon the line 5—5 of Fig. 4 and looking toward the right in said figure.

Referring more particularly to the drawing, the receptacle is indicated at 1 in Fig. 1. It is preferably cylindrical and while it may be of any suitable material is preferably of 40 hard fibre. I have herein represented it as reenforced at each end by a pressed steel band 2, said band being secured at the inner face of the can by bolts 3. Desirably the external ends of the bands 3 are bent over 45 as indicated at 4 to protect the ends of the can 1.

The can is provided with two covers or ends indicated generally at 5 and 6 in Fig. 3. Said covers or ends are provided desirably with a series of feet 7, 7 and 8, 8 so that whichever end of the can be uppermost the locking means for the cover is protected from engagement with the filler.

In the preferred use of the receptacle, it 55 is placed in the upright position shown and

the upper cover (herein 5) is removed, the lower cover (herein 6) being in place. The receptacle is placed at such a point as to receive the chenille or roving as it is discharged from the machine, it being coiled 60 into the receptacle and accumulated therein until the receptacle is filled.

Heretofore so far as I am aware, it has been customary to fill the receptacle in this manner, and then to remove the receptacle 65 and draw out the material therefrom beginning with the end last deposited, thus reversing the accumulating operation. This is objectionable because it is frequently desirable to have access to or to use first that 70 end of the material which is first deposited into the receptacle. This is frequently the case with chenille strands which are frequently colored differentially at various parts of their lengths in accordance with 75 the dictates of the pattern. For example, a red portion of the one integral chenille strip or strand may be coiled at the bottom followed by a blue, this being followed by a yellow portion, and so on. If it be 80 desired to use the first deposited or red portion, it is necessary to withdraw the entire mass of material under the present practice so as to get access to the said red portion. In accordance with my invention, 85 two covers for the roving can are provided, both of which are readily detachable and after filling the receptacle while in the position shown in Fig. 3, I place the cover 5 in position as shown, securing it therein, and 90 then I turn the receptacle end for end and remove the cover 6, thus at once obtaining access to the first deposited end of the chenille or other coiled material.

So far as I am aware, this method of 95 procedure is new and it constitutes an important aspect of my invention.

Obviously any suitable means may be provided detachably to secure the covers 5 and 6 in position. Preferably the same type of 100 means is employed for securing each of the covers, and I will describe the means herein represented for securing the cover 5 in position.

For that purpose, I provide desirably a 105 plurality of clips or holding means 9, 9 secured by rivets 10, 10 to the under face of the cover, as shown in full lines in Fig. 2. At some other point upon the cover intermediate the clips 9, 9 I provide a movable 110

clip or retaining means, which may be readily moved into either holding or releasing position. For this purpose, I preferably slot the cover as indicated at 11, 11 striking 5 up two lips 12, 12 for the sliding reception of the locking piece 13. The said piece is provided with a longitudinal slot 14 represented in Fig. 2, and the cover itself has a similar slot in longitudinal alignment there- 10 with as indicated in dotted lines at 15 in Fig. 2. Upon a pin 16 secured to the cover 5 and receiving the slot 14 is mounted for oscillating movement a locking lever 17 having a protruding end or handle 18 to be 15 engaged by the operator and a head 19 having therein an eccentrically located or cam slot 20 receiving a pin 21 fast upon the slide 13 and received in the slot 15 in the cover. The construction of parts is such that when 20 the locking lever 17 is in the position shown in Fig. 2 the sliding clip 13 is in unlocked position.

Movement of the locking lever 17 in a 25 contraclockwise direction, viewing Fig. 2, results in the movement of the pin 21 along the eccentric slot 20, the formation of which is such as to cause the slide 13 to move inward, thereby bringing said slide into locking position, the locking lever 17 then occupying the position represented in Fig. 1.

Each of the clips 9 is provided with a locking or holding formation 22 and the sliding member 13 is provided with a holding formation 23.

It will be evident from the foregoing description that my invention involves not only a new type of can or receptacle that is peculiarly adapted for use with or for chenille strips, but that it involves a novel process 40 for the manipulation of the chenille strip or like product. It will be understood that in the manufacture of chenille strips the woven fabric is cut into a large number of strips which are rapidly accumulated in cans or receptacles and that great confusion and delay 45 may and do result because of the necessity heretofore existing of removing the entire cans of chenille strips from each receptacle in order to get at the first deposited end 50 thereof.

Having thus described one illustrative embodiment of my invention, I desire it to be understood that although specific terms are employed, they are used in a generic and 55 descriptive sense and not for purposes of limitation, the scope of the invention being set forth in the following claims.

Claims:

1. A can or receptacle for the reception of chenille strands or the like comprising 60 a body, a cover at at least one end thereof and having a face whereon the can or receptacle may stand upright, fixed overhanging lugs and movable securing means carried by said face of said cover, said means engaging the outer portion of the can or receptacle to stress the cover laterally and thereby hold the said lugs in holding engagement and means for positively moving said movable securing means into holding 65 engagement.

2. A can or receptacle for the reception of chenille strands or the like comprising a body, a cover at each end of the body, means upon the face of each cover for locking said cover in position, the said cover and its locking means being constructed and arranged to permit the can or receptacle to stand evenly upon either end when the cover 75 is in position thereat and upon said cover 80 as a base.

3. A can or receptacle for the reception of chenille strands or the like comprising a body, a cover at each end of the body, said cover having feet to support the body upright, and securing means for each cover at the face thereof and shaped and arranged to permit the receptacle to stand either end 85 down upon the feet of the cover at the then lower end.

4. A can or receptacle for the reception of chenille strands or the like comprising a body, a cover for at least one end thereof, fixed securing means for said cover and locking means including a member movable radially of the cover upon the inner face thereof, a lever pivoted upon the outer face of said cover and provided with a cam slot, said movable member having a portion extending through the cover and received in said slot. 100

5. A can or receptacle comprising a body open at each end, one or more closure members each applicable interchangeably to either end of said body, each closure member provided with locking means engageable with the sides of said body and mechanism upon its outer face for operating said locking means, and means upon each closure member whereby it may serve as a base for the upright support of the body when in position 105 at the then lower end of the same.

In testimony whereof, I have signed my name to this specification.

EDGAR F. HATHAWAY.

Certificate of Correction.

It is hereby certified that Letters Patent No. 1,489,668, granted April 8, 1924, upon the application of Edgar F. Hathaway, of Dorchester, Massachusetts, for an improvement in "Cans or Receptacles for the Reception of Chenille Strands or the Like and Processes of Using the Same," were erroneously issued to the inventor, said Hathaway, whereas said Letters Patent should have been issued to *Shawmut Engineering Company, of Dorchester, Massachusetts, a Corporation of Massachusetts*, as shown by the records of assignments in this Office; and that the said Letters Patent should be read with this correction therein that the same may conform to the record of the case in the Patent Office.

Signed and sealed this 15th day of July, A. D. 1924.

[SEAL.]

THOMAS E. ROBERTSON,
Commissioner of Patents.
